UNITED STATES PATENT OFFICE.

CHARLES M. FRENCH, OF BROOKLYN, NEW YORK, ASSIGNOR TO CABINET MAKERS, INC., OF NEW YORK, N. Y., A CORPORATION OF NEW YORK.

DESIGN FOR A RADIOCABINET OR SIMILAR ARTICLE.

Application filed June 4, 1925, Serial No. 13,653. Term of patent 3½ years.

To all whom it may concern:

Be it known that I, CHARLES M. FRENCH, a citizen of the United States, residing at Brooklyn, in the county of Kings and State of New York, have invented a new, original, and ornamental Design for Radiocabinet or Similar Article, of which the following is a specification, reference being had to the accompanying drawing, forming a part thereof.

Fig. 1 is a front view of a cabinet showing my new design, and Fig. 2 is a side view of Fig. 1.

I claim:

The ornamental design for a radiocabinet or similar article, as shown.

CHARLES M. FRENCH.
